United States Patent Office.

EDWARD P. RYDER, OF NEW YORK, N. Y.

Design No. 4,849, dated April 25, 1871.

DESIGN FOR A TOY STEAM-ENGINE.

The Schedule referred to in these Letters Patent and making part of the same.

To all whom it may concern:

Be it known that I, EDWARD P. RYDER, of the city, county, and State of New York, have invented and produced a new and original Design for Toy Steam-Engine, of which the following is a specification.

The nature of my design is fully represented in the accompanying drawing, to which reference is made, and in which—

Figure 1 is a side elevation of a toy steam-engine, made in accordance with my design.

Figure 2 is an end view of the same.

In the drawing similar letters of reference designate like parts of the invention.

A shows the boiler, supported by the uprights B secured upon a base-plate, C, which boiler is provided with an opening, *a*, to allow water to be introduced into the same.

D shows the frame for supporting the cylinder E of the engine, formed upon the top or upper part of the boiler A.

The portion of the frame D intended to support the cylinder E is provided with an opening, through which the cylinder-trunnion F is passed, and also with an

exhaust-port and a steam-port communicating with the cylinder E.

Through the front portion of this frame D is passed the shaft G, supporting the fly-wheel H, and upon a pin, *i*, secured in the fly-wheel, is hung one end of the piston J, moving freely in the cylinder E.

Over a hook, K, secured in the boiler-head, is passed the bent end of a helical spring, L, while the opposite end of this spring L is passed through an opening in the cylinder-trunnion F, and serves to hold the cylinder in position upon the frame D.

The operation of a toy steam-engine constructed in accordance with the design just set forth can be so readily understood by all familiar with the operation of a steam-engine that a description of it hardly seems necessary.

What I claim as my invention is—

The design for a toy steam-engine, as shown.

EDWARD P. RYDER.
